J. FLETCHER.
BRAIDING MACHINE.

No. 39,138.

Patented July 7, 1863.

UNITED STATES PATENT OFFICE.

JOSEPH FLETCHER, OF PROVIDENCE, RHODE ISLAND.

IMPROVEMENT IN BRAIDING-MACHINES.

Specification forming part of Letters Patent No. 39,138, dated July 7, 1863.

To all whom it may concern:

Be it known that I, JOSEPH FLETCHER, a citizen of the United States of America, and a resident of the city and county of Providence, and State of Rhode Island, have invented a new and useful Improvement in the Braiding-Machine; and I do hereby declare the same to be fully described in the following specification, and represented in the accompanying drawings, of which—

Figure 1 is a top view of a racer and the race portion of a braiding-machine, as provided with my invention. Fig. 2 is an end elevation of the same. Fig. 3 is a vertical section thereof. Fig. 4 is a side view of the racer. Fig. 5 is a side view of an ordinary racer. Fig. 6 is an under side view of the lapping or recessed plate, to be hereinafter described.

The nature of my invention consists in an improvement in the braiding-machine, such consisting in having the racer and its driving-wheels and the supports of the racer so constructed that the weight of the racer shall be borne on each of the driving-wheels, while such driving-wheel may be in the act of driving the racer.

My invention further consists in the combination of a recessed plate, or its equivalent, with the racer-base and the driving wheel or gear, such plate being made to overlap the base of the racer, to move with the driving-wheel, and to prevent the racer from swaying laterally while in motion.

The purpose of my invention is not only to afford a better support to the racer than it usually has, but also to prevent the bearing and friction of the racer on the top surface or surfaces of the raceway or the race-plates thereof.

In the drawings, A is the race-plates and raceway, while B is the racer. The bottom or lower part of the racer, instead of being a cylindrical stud or projection, as shown at *a* in Fig. 5, is a flat plate or base, as shown at *b* in Fig. 4 and in Fig. 7, which is an under side view of such bottom. This flat bottom or base extends each way from a neck, *c*, which

is to run in the groove or raceway *d* of the race-plates A. The said flat base *b* rests on the upper surface of the driving-gear wheel C. There is a train of these gears C which engage with one another, and operate to force the racer through the curved tracks of the raceway. These gears are arranged with respect to such raceway as they are in ordinary braiding-machines, and there is between each of them and the race-plate over it a recessed plate, D, whose lower face is recessed or provided with four recesses, *d d d d*, formed to receive the projecting base of the racer and overlap it, as shown in Fig. 3. When the base extends into any one of the recesses, the latter not only serves to drive the racer through the raceway during revolution of the gear, but keep the racer upright and prevent it from swaying in its groove.

From the above it will be seen that the racer, by being supported directly on the gear, travels with it, and does not bear on the top surface or surfaces of the race-plates. In this way the friction and wear of the racer on the upper surfaces of the race-plates are avoided, and the machine is not only run with less power, but with less friction and more certainty of correct operation.

I claim—

1. An improvement in the braiding-machine, the same consisting in having the racer and driving wheels or gears and the supports of the racer so constructed that the weight of the racer shall be borne on each of the said driving-gears while in the act of being driven by such gear.

2. The combination of the recessed plate D, or its equivalent, with the racer-base *b* and the driving wheel or gear C, on which such plate is affixed, such plate being for the purpose and to operate in manner substantially as hereinbefore explained.

JOSEPH FLETCHER.
